UNITED STATES PATENT OFFICE.

CHARLES C. BLAKE, OF BROOKLINE, MASSACHUSETTS, ASSIGNOR TO C. C. BLAKE,
INCORPORATED, OF BOSTON, MASSACHUSETTS, A CORPORATION OF NEW YORK.

SHOE.

1,284,857.

Specification of Letters Patent. Patented Nov. 12, 1918.

Original application filed August 16, 1913, Serial No. 785,142. Divided and this application filed March 11, 1914. Serial No. 823,865.

To all whom it may concern:

Be it known that I, CHARLES C. BLAKE, a citizen of the United States, residing at Brookline, in the county of Norfolk and State of Massachusetts, have invented new and useful Improvements in Shoes, of which the following is a specification.

The present invention relates to means for connecting members together such, for instance, as the shoe upper, welt and insole of a welt shoe.

Such insoles are usually prepared for the sewing operation, that is, the operation of securing the shoe upper, welt and insole together, from a sole shaped blank by splitting it along its edge around the shank and forepart to form a lip and a feather or by splitting its edge and also cutting one face of the blank within the edge cut thereby forming a flap parallel to the lip. The lip or lip and flap are turned up at right angles to the cut face of the blank to form a marginal abutment the base of which receives the stitches during the sewing operation. After the sewing and inseam trimming operations the cavity bounded by the marginal abutment hereinbefore referred to is filled with ground cork mixed with a suitable binder. This construction permits the shoes to be exhibited to the trade with the forepart of the insoles in a flat condition. As soon, however, as these shoes are worn the cork filler becomes displaced in the space between the inner and outer soles resulting in the formation of a concave trough in the forepart of the insole. The formation of a trough in the forepart of the insole and the presence of the marginal feather or abutment are sources of great discomfort and injury to the feet.

I propose to prevent the formation of this objectionable trough in the forepart of the insole by eliminating the necessity for the formation of a marginal abutment to receive the inseam stitches and consequently the need of using a filler between the inner and outer soles to fill the cavity bounded by the marginal abutment. As a substitute for the marginal abutment to hold the inseam stitches I employ tongues formed in one face of the insole over which the thread connecting the welt, upper and insole of a welt shoe or the sole and upper of a turn

shoe is looped. It has been proposed heretofore to employ tongues to hold the stitches in both welt and turn shoes, but the construction of the tongues and the methods employed for their formation have been found impracticable.

The method employed in forming the tongues for holding the stitches in turn shoes consisted in providing a sewing machine with a V-shaped chisel which cut a V-shaped incision in the face of the sole thus forming a tapering V-shaped tongue integral therewith over which the thread connecting the upper and sole was looped. This method was found impracticable, however, as it proved to be impossible for the operative to hold the shoe in his hand and swing and tip the shoe at the proper time and to the proper extent so that the chisel would uniformly penetrate the sole at the correct angle and depth. It was found that any deviation in the angle or depth of cut seriously affected the size or position of the tongues which prevented the sewing instrumentalities from properly handling the thread and setting it in position over the tongues. As these tongues also taper in width and thickness throughout their length it was found impossible to properly set the thread in position thereover, even when correctly formed, as the tension with which the stitch was set caused the tapered tongue to buckle and thus permit the thread to slip therefrom.

For welt work it was proposed to first channel the insole and then slit the channel flap transversely into short sections, the alternate ones of which were used as tongues. While by this method tongues were formed having a uniform width throughout their length this method also proved to be impracticable as it involved a separate channeling operation and it produced tongues tapering in thickness which in the same manner as the V-shaped tongues permitted the tongue to buckle under the tension employed in setting the stitch and the thread to slip therefrom.

An important object of the present invention is to provide one member of the parts to be connected with tongues constructed to hold the stitches in a reliable and satisfactory manner.

- 2
- To the accomplishment of this object and such others as may hereinafter appear the features of the invention relate to certain constructions, arrangements and methods of manufacture hereinafter described and then set forth broadly and in detail in the appended claims which possess advantages readily apparent to those skilled in the art.
- 5 While the invention may be utilized to manufacture hereinafter described and then set forth broadly and in detail in the appended claims which possess advantages readily apparent to those skilled in the art.
- 10 While the invention may be utilized to connect various components of an article together, I have selected an insole and the manner of its connection with the shoe upper and welt of a welt shoe for the purpose of illustration as it shows the invention in its best form at present devised.
- 15 The various features of the present invention will be readily understood from an inspection of the accompanying drawings in which:
- 20 Figure 1 is a plan of an insole provided with a series of furcular slashes along the peripheral margin of one face;
- 25 Fig. 2 is a detail elevation, partly in section, showing the manner in which the furcular slashes are formed in the insole;
- 30 Fig. 3 is a perspective of the gouge employed to slash the insole;
- 35 Fig. 4 is a detail plan showing the awl penetrating the edge of the insole, intersecting the slash below the surface of the insole, and separating the tongue bounded by the tires of the fork, the face of the insole and the awl cut, from the body portion of the insole;
- 40 Fig. 5 is a detail sectional elevation of the parts illustrated in Fig. 4;
- 45 Fig. 6 is a sectional elevation similar to Fig. 5 showing the awl withdrawn;
- 50 Fig. 7 is a detail plan showing the passing of the thread through the welt, upper and insole by means of a needle;
- 55 Fig. 8 is a perspective, partly in section, showing the operation of the needle which enters the work in the split of the welt and emerges from the face of the sole through the stem of the furcular slash;
- 60 Figs. 9, 10 and 11 are elevations, partly in section, showing various positions of the looper in looping the thread over the tongue and subjecting the tongue to pressure; and,
- 65 Fig. 12 is a perspective, partly in section, of the finished shoe embodying the features of the present invention.
- In the illustrated embodiment of the invention an insole 1 is provided with a series of furcular slashes 2 which are formed normal to one face of the insole along the peripheral margin thereof. These furcular slashes may have any forked construction either with or without a stem, as may be found desirable or expedient. That is, they may take the form shown at A, or B, or C, (Fig. 1). It is preferred, however, to employ a slash of the type shown at C which 65 comprises a fork 3, having two tines 4, and a stem 5 connected to the fork. The insole is also provided with a series of awl cuts 6, (Fig. 6) each one of which extends parallel to the slashed face of the insole from the edge of the insole to one of the slashes which it intersects below the surface of the insole thus separating the material of the insole bounded by the tines 4 of the fork from the body portion of the insole and forming a tongue 7, (Figs. 5, 6 and 7) integral therewith. As the furcular slashes and awl cuts are formed normal to the face and edge of the insole respectively the sides of the tongues are perpendicular to the face of the insole and the top and bottom faces of the tongues are parallel. This construction produces a tongue uniform in width and thickness substantially throughout its length thus insuring a substantial piece of stock to hold the stitches. With this construction all danger of the tongue buckling so that it can be pulled back into the awl cut when the stitch is being set, thus permitting the thread to slip from the tongue, is obviated.
- 70 75 80 85 90 95 100 105 110 115 120 125 130
- With the insole thus prepared it may be connected to a shoe upper and welt in any suitable manner found desirable or expedient. Preferably a shoe upper 8 is secured in lasted position to the edge face of the insole in which position it is interposed between the insole and a welt 9 so that the edge of the upper is substantially flush with the tread or bottom faces of the insole and welt and with the contacting faces of the welt and upper and of the upper and edge face of the insole arranged in parallel planes normal to the face of the insole. The upper, insole and welt are connected together by a thread 10 which extends progressively along a longitudinal slit 11, formed in the welt 9, through the welt, upper and insole, over the tongue 7 and back through the insole, upper and welt to the slit therein. As shown in Fig. 6 the slit 11 in the welt is formed in the same plane as the bottoms of the tongues in the insole. Since the bottom faces of the welt and insole and the free edge of the upper lie substantially flush, they form a smooth continuous surface to bear on the upper face of the outsole in the finished shoe (Fig. 12).
- While in its broader aspects the invention contemplates preparing the insole with tongues prior to the sewing operation, it is preferred to form the tongues in the machine which connects the shoe upper, welt and insole together. To this end the machine preferably is provided with a gouge 12, (Figs. 2 and 3) arranged to reciprocate at right angles to the face of the insole and provided with two cutting edges one of which, the edge 13, forms the stem of the furcular slash and the other one of which, the edge 14, forms the fork with its two tines. In order to limit the depth of the

slash the gouge carries a block 15 which strikes against the surface of the insole during the downward movement of the gouge, (Fig. 2). After the gouge 12 forms the 5 slash it is withdrawn, and an awl 16 is actuated in the plane of the slit 11 through the welt, upper and insole, (Figs. 4 and 5). The awl cut intersects the slash below the 10 surface of the insole and penetrates the insole beyond the juncture of the stem and fork thus forming a tongue from the material bounded by the tines of the fork. As shown in Fig. 4 the width of the awl is greater than the distance between the tines 15 of the fork in order to form a clean line of demarcation between the tongue and the body portion of the sole. As the block 15 limits the downward movement of the gouge in the same manner for each succeeding 20 slash, and as the gouge and awl operate normal to the face and edge of the insole, respectively, it will be apparent that the tongues are uniformly formed, a result heretofore considered impossible.

25 As soon as the awl withdraws, a straight eye-pointed needle 17 carrying the thread passes through the awl cut formed in the welt, upper and sole finally emerging through the stem of the slash above the 30 surface of the insole, (Figs. 7 and 8). After the needle has passed completely through the work in the manner illustrated in Fig. 8 it is withdrawn from the work and forms a loop in the thread. During the first part 35 of the return stroke of the needle the loop is engaged by a nose 18 formed upon an oscillating looper 19. The looper first oscillates in the direction of movement of the retreating needle to throw the loop over one 40 of the tongues, (Fig. 9). Just before the thread is looped over the tongue the looper is dropped upon the tongue, (Fig. 10), and then when the needle withdraws from beneath the tongue, the looper is oscillated in 45 the reverse direction which causes the looper to release the thread and to wipe over the tongue and depress it substantially flush with the surface of the sole, (Fig. 11), after which the looper is returned to its original 50 position. The stitch is now set by drawing the thread taut over a part of the tongue close to its base.

55 Those skilled in the art will readily appreciate from an inspection of Fig. 12 the important advance in the art of shoe making initiated by the present invention. A shoe embodying the features of the present invention is more comfortable to wear than welt shoes heretofore devised as the construction thereof eliminates the plastic filler between the insole and outsole and thus avoids both the possibility of the formation of the objectionable trough in the forepart of the insole and also the presence of the marginal 60 feather or abutment which frequently causes

discomfort. It is also more economical to manufacture as a large number of the operations heretofore considered essential in the formation of welt shoes are eliminated, particularly those operations formerly employed to prepare the insole for the sewing operation and to fill the cavity between the inner and outer soles. It will readily be apparent to those skilled in the art that the shoe of the drawings is more flexible than 70 the shoes made by the Goodyear process since the stiff rib for holding the stitches is eliminated. This flexibility is further increased by the stems of the furcular slashes formed in the insole. For many reasons obvious to those skilled in the art the shoe illustrated in Fig. 12 is more durable than the welt shoes heretofore devised. One reason for this is that the inseam stitches of 75 the improved shoe are arranged substantially in the plane of flexure of the shoe while in the former welt shoe the inseam stitches were not so arranged and consequently were subjected to strain every time 80 the shoe flexed in walking.

85 While it is preferred to employ the specific construction, arrangement and method of manufacture shown and described, it will be understood that this specific construction, arrangement and method of manufacture is not essential nor is the conjoint 90 use of all the features of the invention essential except so far as specified in the appended claims and it may be varied or modified without departing from the broader 95 features of the invention.

90 It will also be apparent to those skilled in the art that the present invention is useful in the manufacture of other kinds of shoes than welt shoes, therefore, the term "sole" 100 used in the following claims must be construed to mean any kind of a sole whether an insole or an outsole.

105 What is claimed as new, is:—

110 1. A sole provided with a series of furcular slashes normal to one face thereof, substantially as described.

115 2. A sole provided with a series of furcular slashes formed along the peripheral margin of one face, each slash comprising a fork and a stem, substantially as described.

120 3. A sole provided with a series of slashes formed along the peripheral margin of one face, each slash comprising a fork and a stem, and a series of awl cuts formed in the edge of the sole co-operating with the tines of the forks to form stitch-anchoring tongues, the stems of the slashes imparting flexibility to the sole when the tongues are stiffened with stitches, substantially as described.

125 4. A sole provided with a series of furcular slashes normal to one face thereof, and a series of awl cuts formed in the edge of the sole parallel to the slashed face, each 130

- cut being arranged to intersect one of the slashes below the surface of the sole, substantially as described.
5. A sole provided with a series of furcular slashes formed along the peripheral margin of one face, and a series of awl cuts formed in the edge of the sole, each cut being arranged to intersect one of the slashes below the surface of the sole and form a tongue from the material of the sole bounded by the tines of the slash, the face of the sole, and the cut, substantially as described.
6. A sole provided with a series of furcular slashes formed along the peripheral margin of one face, and a series of awl cuts formed in the edge of the sole, each cut being arranged to intersect one of the slashes below the surface of the sole and having a width substantially greater than the distance between the tines of a fork, substantially as described.
7. A sole provided with a series of tongues formed along the peripheral margin of one face, and a series of awl cuts formed in the edge of the sole, each cut forming the bottom of a tongue and having a width substantially greater than the width of a tongue, substantially as described.
8. A sole provided with a series of tongues uniform in thickness throughout their length, substantially as described.
9. A sole provided with a series of tongues each uniform in width substantially throughout its length, each tongue being separated from an adjacent tongue by an uncut portion of the sole, substantially as described.
10. A sole provided with a series of tongues formed along the peripheral margin of one face, and a series of awl cuts formed in the edge of the sole, each cut being wider than a tongue and formed in the plane of the bottom of the tongue adjacent thereto, substantially as described.
11. A sole provided with a series of furcular slashes, each comprising a fork and a stem, the material bounded by the tines of the forks forming tongues to hold the stitches, and the stems of the slashes permitting a needle to emerge from the sole therethrough, substantially as described.
12. A sole provided with a series of tongues each tongue having its sides arranged normal to the face of the sole and its top and bottom faces arranged in parallel planes, substantially as described.
13. A sole provided with a series of two co-operating cuts each pair of cuts being formed in the face and edge of the sole respectively normal to each other and intersecting below the surface of the sole, substantially as described.
14. A shoe, having, in combination, an upper, an insole provided with a series of tongues, and a welt provided with a longitudinal slit formed in the same plane as the bottoms of the tongues in the insole, substantially as described.
15. A shoe, having, in combination, an upper, an insole provided with a series of tongues, and a welt provided with a longitudinal slit formed in the same plane as the bottoms of the tongues of the insoles, said parts being secured together with the bottoms of the insole and welt substantially flush, substantially as described.
16. A shoe, having, in combination, an upper, a welt, and an insole provided with a series of tongues, said parts being secured together by stitches looped over the tongues with the bottom faces of the welt and insole and the free edge of the upper substantially flush, substantially as described.
17. A shoe, having, in combination, an upper, an insole provided with a series of tongues, a welt provided with a longitudinal slit, and a thread passing progressively along the slit in the welt, through the welt, upper and insole, and over a tongue, returning to the slit in the welt through the insole, upper and welt, substantially as described.
18. In combination two members one of which is provided with one or more furcular slashes near its edge and both of which are provided with one or more cuts intersecting the slash or slashes below the surface of the slashed member to free the material bounded by the fork or forks from the body portion of the slashed member and form a tongue or tongues therefrom whereby a thread passed through the cuts formed in the members may be looped over the tongue or tongues, substantially as described.
19. A sole provided with a series of tongues each uniform in width and thickness substantially throughout its length, substantially as described.
20. A sole having a series of uniform stitch-anchoring tongues formed in one face thereof, each tongue being separated from an adjacent tongue by an uncut portion of the sole, substantially as described.
21. A shoe, having, in combination, an upper, a sole provided with tongues and a strip overlying the upper, said parts being secured together by stitches anchored in the strip and in said tongues formed in the sole with the lower faces of the strip and sole arranged in the same plane, substantially as described.
22. As an article of manufacture, a flexible foot engaging sole for boots and shoes having stitch anchoring means and a series of transverse slashes in its flesh side at the shank arranged radially with respect to the edge of the shank, said flesh side being unchanneled, substantially as described.
23. A sole of the character described, having a series of stitch-anchoring tongues

formed along the margin of one face thereof, each tongue being of approximately uniform transverse cross sectional area for a substantial portion of its length adjacent to its base.

5 24. A welt shoe, having, in combination, a welt slit longitudinally along one edge; an insole; and an upper secured to the edge face of the insole, said parts being secured together by a single thread, passed along the 10 slit in the welt and through the welt, upper and insole, said thread having no portions thereof interlocked with other portions of the thread.

25. A welt shoe, having, in combination, a 15 welt slit longitudinally along one edge; an insole; and an upper secured to the edge face of the insole, said welt being secured to the united upper and insole by means other than the means uniting the upper and insole with the unslit edge of the welt, the opposite faces of the marginal portion of the upper and the edge face of the insole in parallel planes normal to the face of the insole.

26. A welt shoe, having, in combination, a 20 welt slit longitudinally along one edge; an insole; and an upper secured to the edge

face of the insole, said welt being secured to the united upper and insole by means other than the means uniting the upper and insole with the contacting faces of the welt and 30 upper and of the upper and insole in parallel planes normal to the face of the insole.

27. A step product of the inseaming operation in the manufacture of a welt shoe comprising an upper secured to the edge face of 35 the insole, and a welt secured to the united upper and insole by means other than the means uniting the upper and insole.

28. A step product of the inseaming operation in the manufacture of a welt shoe comprising a lasted upper united to the edge face of the insole, and a welt slit longitudinally along the edge face of the welt which is exposed in the finished shoe and secured to the united upper and insole by stitches 40 45 anchored in the base of the slit in the welt and also in the insole.
